WILLIAM T. M. BESSON, OF SELMA, ALABAMA, ASSIGNOR OF ONE-HALF TO H. A. VAUGHAN, OF SELMA, ALABAMA.

SPARK-PLUG.

1,119,674.

Specification of Letters Patent.

Patented Dec. 1, 1914.

Application filed December 15, 1913. Serial No. 806,936.

To all whom it may concern:

Be it known that I, WILLIAM T. M. BESSON, a citizen of the United States, residing at Selma, in the county of Dallas and State of Alabama, have invented certain new and useful Improvements in Spark-Plugs, of which the following is a specification.

This invention relates to spark plugs, and an object of the invention is to provide a spark plug so formed as to prevent the interference with the spark by the accumulation of oil on the electrodes.

A further object of the invention is to provide the active portion of the spark plug in a continuous surface so that the oil which collects thereon may drip from the bottom of the plug, and not remain in any objectionable quantities on the active portions of the plug.

With these and other objects in view, the invention consists in certain constructions, combinations and arrangements of the parts as will be hereinafter fully described and claimed.

The accompanying drawing shows a vertical central section taken through the spark plug.

The general aim of the present invention is to provide a spark plug the depending portion of which is provided with a smooth surface which terminates in a conical point so that oil accumulating upon the surface will drip from the point. The points between which the spark jumps, are removed somewhat from the point of the plug.

Referring more particularly to the drawings, it will be seen that the hollow threaded tube 1 which is threaded into the walls of the engine cylinder, has the lower end thereof pointed in the shape of a cone as at 2. The insulating material 3 is shaped so as to conform to the interior of the tube 1, and has a conical point so that the surface between the vanishing edge 4 of the conical point 2 of the threaded tube, lies against the conical surface 5 of the insulating material. It will be understood of course that the grounded side of the ignition system will be connected to the tube 1. The other side of the ignition system comprises a wire 6, the point of which is conical as shown at 7, the point 7 vanishing as at 8.

It will be understood from the drawing

that the surface between the conical end 2 of the threaded tube, the conical surface of 55 the insulating material, and the conical surface of the point 7, forms altogether substantially a conical surface smooth in contour so that oil may run from the grounded electrode to the insulating material, and from 60 there on to the larger point of the conical point 7 from where it will go to the point 8 and drop off into the cylinder. It will be seen that the desirable feature is that the surface formed by the exterior of the 65 grounded electrode insulator, and the point 7 shall be smooth, and it is apparent that it is not necessary that the parts of the spark plug be formed exactly as shown in the drawings to accomplish this result. 70

The invention which resides in the particular formation of the point of the spark plug, may be applied to any style of spark plug, and for that reason no particular description will be given hereinafter concerning the remaining portions of the spark plug. The conical end of shell 2 may be formed of steel, while the electrode 6 may be made of any material, and it will be noted that the exposed portion of the insulator 3 80 spaces the grounded electrode from the electrode 6. 75

What I claim is:

1. A spark plug for internal combustion engines comprising a tube provided with a 85 hollow downwardly extending pointed end, a pointed insulating member located within the tube and extending beyond and below said hollow pointed end of the tube, and a conductor extending downwardly below the 90 insulator and having a conical pointed end the length of which is considerably greater than the widest part of the conical end, the surface of which is contiguous with the surface of the insulator and exposed to the 95 heat of explosion.

2. A spark plug for internal combustion engines comprising a tube having an outer downwardly extending conical surface, a conductor extending through the tube having a pointed end of greater length than the thickest part thereof projecting downwardly into the cylinder, an insulator interposed between the tube and the conductor and having a portion of the surface thereof 100 located between the tube and the pointed 105

end of the conductor, said surface of the insulator producing with the said surface of the tube and the surface of the pointed end of the conductor an unbroken downwardly pointing conical surface, the pointed end of the conductor being isolated from the tube and the insulator.

In testimony whereof I affix my signature in presence of two witnesses.

WILLIAM T. M. BESSON.
